UNITED STATES PATENT OFFICE.

ELDRIDGE STANTON, OF TORONTO, ONTARIO, CANADA.

LOOSE-LEAF BINDER.

1,039,207.

Specification of Letters Patent. Patented Sept. 24, 1912.

Application filed June 21, 1911. Serial No. 634,627.

To all whom it may concern:

Be it known that I, ELDRIDGE STANTON, of the city of Toronto, in the county of York, in the Province of Ontario, Canada, 5 have invented certain new and useful Improvements in Loose-Leaf Binders, of which the following is the specification.

My invention relates to improvements in loose leaf binders, and the object of the 10 invention is to devise a binder of this class which will be neat in appearance capable of being easily separated for the insertion of new leaves or for removing leaves therefrom and it consists essentially of a U-shaped 15 channel strip having inturned edges and holes extending through the base of the strip and designed to register with the holes in the loose leaves, a flexible metallic strip designed to extend at each end through the 20 holes of the leaves and through the holes in the strip and bent downwardly so as to rest upon the base of the strip and a supplemental covering strip designed to fit within the U-shaped strip over the ends of the 25 metallic strip as hereinafter more particularly explained by the following specification.

Figure 1, is a general perspective view of my binder edging and cover with loose 30 leaves inserted within the cover. Fig. 2, is a similar view to Fig. 1, showing the binder separated. Fig. 3, is an enlarged longitudinal section through the binder leaves and cover, such figure being intermediately 35 broken away. Fig. 4, is a cross section on line $x-y$ Fig. 3. Fig. 5, is a perspective view of one end of the binder as it would appear prior to removing leaves. Fig. 6, is a longitudinal section showing my device 40 adapted to be used without the cover as shown in Figs. 1 to 5.

In the drawings like letters of reference indicate corresponding parts in each figure.

A is one cover member to which is secured 45 by eyelets A³ or by other suitable means a metallic strip A⁴. B is the other cover member to which is secured by eyelets B' or other suitable means a metallic strip B².

C are the loose leaves.

D and D' are U-strips having inturned 50 edges D² and holes D³ extending through the base of the strip D⁴.

E are strips of flexible metal preferably provided with pointed ends E'. The flexi-

ble metal strip is threaded through the 55 holes D³ of both strips D' and D and through the holes C' and the loose leaves C as shown in Figs. 3, 4 and 5. The ends E' extend upwardly as shown in Fig. 5 and are bent down against the base D⁴ of the strip 60 D. The bars A⁴ and B² are then slid into the U-strips D and D' thereby securely holding the ends E' of the strip in place and effectually covering the same so as to 65 form a neat appearance.

It will be seen that when it is necessary to put new leaves in the cover all that I have to do is to slide the strips A⁴ and B² of the covers and the cover members attached thereto longitudinally and bend the 70 ends E' of the strip E upwardly and then the leaves may be removed and new ones inserted in place thereof if desired.

In Fig. 6, I show my device adapted for 75 permanently binding a set of loose leaves together. In this instance I turn up the ends A⁶ of the strip A⁴ so as to prevent the strips sliding longitudinally within the U-strip D. By this means the leaves are 80 permanently bound together.

From this description it will be seen that I have devised a very simple device which is convenient both for temporary holding 85 loose leaves together in a temporary cover so as to have a neat appearance and yet be absolutely secure and also by the same means for permanently binding loose leaves together if desired.

What I claim as my invention is.

In a loose leaf binder, the combination 90 with the separate cover members and the loose leaves, of a U-shaped strip located to each side of the loose leaves having opposing internal longitudinal grooves and having perforations extending through the base 95 of the strip, flexible metal strips extending at each end through the leaves and through separate perforations in the U-shaped strip, and bent over at the ends onto the base of the U-shaped strip and a flat cover strip 100 secured to each cover member and adapted to slide longitudinally into the opposing internal grooves of the U-shaped strip, as and for the purpose specified.

ELDRIDGE STANTON.
